ATTORNEY

UNITED STATES PATENT OFFICE.

ALEXANDER MASZTICS, OF NEW YORK, N. Y.

MOLDING APPARATUS.

Application filed December 8, 1926. Serial No. 153,413.

This invention relates to a molding apparatus.

An object of the invention is to mold simultaneously a relatively large number of blocks and the like and give said blocks any desired ornamental surface.

A further object is to provide an improved apparatus in which wet blocks are dried or set in contact with a facing or ornamental material which adheres thereto during the setting operation.

A further object is to provide an apparatus which enables the quick formation of a relatively large number of small building blocks, which can be easily and conveniently used in building structures and which will be relatively light so that they may be easily handled by the workmen and broken to fit odd places.

With these and other objects in view, the invention consists in certain novel features of construction and certain novel steps in the process, all of which will be more fully hereinafter described and pointed out in the claims.

In the accompanying drawings—

Figure 1 is a plan view, showing my improved mold or apparatus with the parts assembled therein;

Figure 2 is a view similar to Figure 1, showing the parts in position after the complete operation of molding is carried out;

Figure 3 is a view in vertical section on the line 3—3 of Figure 2, the covering frame being shown in dotted lines;

Figure 4 is a view similar to Figure 3 but showing the molding apparatus complete and in inverted position;

Figure 5 is a view similar to Figure 4, showing the molded blocks completed and drying;

Figure 6 is a perspective view of the mold covering frame;

Figure 7 is a perspective view of one of the mold elements;

Figure 8 is a perspective view of one of the core elements;

Figure 9 is a perspective view of one of the spacers.

I shall first describe the apparatus I employ and later the process as it is carried out step by step.

I employ a mold box 1 with a top 2 and bottom 2' adapted to fit thereon, said box as a whole coupled by rods 3 with nuts 4 on their respective ends to clamp the assemblage

together. The bottom 2' of the box 1 carries a plurality of core members 5 which are hollow and preferably tapering and of relatively thin metal, and adapted to receive sand therein, as indicated at 6. These core members 5 are formed with studs 7 which project through the bottom 2' of the box 1 and are securely clamped by nuts 8 on the ends of the studs.

In connection with these core members 5 I employ mold elements 9 which are of relatively thin metal of preferably larger diameter than the core members 5, open at both ends and preferably angular in form, the core members 5 being circular in cross section.

It is to be understood that my mold members or elements 9 are preferably longer than the core members 5 and receive the core members therein, leaving a space around the core members for the formation of the block between the core member and the mold member or element 9. These assemblages of core members 5 and elements 9 may be provided in any desired number and arranged in any desired manner within the mold box, but they are preferably arranged in parallel lines, equally spaced apart, and are adapted to be held in this relationship by spacers 10.

Most of these spacers are of general cross shape in cross section so that they receive the corners of the mold members 9, and others of the spacers at the edges of the mold box are made of general T-shape or angular shape in cross section so as to fit within the box and maintain the mold members 9 properly spaced apart.

A covering frame 11 is adapted to fit on top of the series of mold members 9, having openings 12 therein to register with the interior of the mold members 9 and covering the spaces between said mold members 9.

In operation, the mold box is in the position shown in Figure 1. The core members 5 being first filled with sand are located centrally in the mold members 9 and the latter are held apart by the spacers 10.

The first step in the operation of molding is to place the frame 11 over the assemblage indicated in Figure 1 and then pour a cementitious material into all of the mold members 9 around and over the core members 5 to form blocks 13. The next step is to remove the covering frame 11 and all of the spacers 10 and then fill in the entire mold box around the outside of all of the mold

elements 9 with fine sand, pulverized marble, cinders, ground coal, or any other material 14 of any color desired which may be utilized to form an ornamental surface on the blocks.

5 After the mold is completely filled with this surfacing material the top 2 is placed on the box 1 and securely clamped by the rods 3 and nuts 4. The next step is to invert the mold box to the position shown in Figure 4.

10 The upper nuts 4 are then removed and the bottom of the mold box is lifted off, leaving the box supported on the normal top with the parts in the position shown in Figure 5. However, this Figure 5 shows the position 15 of the parts after the mold members or elements 9 are drawn vertically off of the blocks, as this is done as soon as the mold as a whole is inverted and before the blocks are set. When these mold members or elements 9 are drawn off of the blocks, the surfacing material which is disposed around all 20 of the blocks will come in contact with the blocks while they are wet and will adhere to the surface of the blocks so that as the 25 blocks become set they will have imparted thereto an ornamental surface which may be of pulverized marble or any other suitable material.

It is to be understood that when the core 30 members are removed, the sand which is enclosed therein will flow out and provide a sand core within the interior of the blocks, and when the elements 9 are withdrawn the surfacing material will provide a support 35 for the outer portions of the blocks so that the latter may become set while held internally and externally by the sand and surfacing material, respectively, as indicated clearly in Figure 5.

40 The box 1 is of course made in sections and separable to facilitate the removal of the molded blocks after they are set, and by means of this process a large number of relatively small blocks can be easily, quickly and 45 efficiently made by any one of average intelligence, and any surface ornamentation given to the blocks by direct contact of said surfacing material with the wet blocks while they are drying or setting. As the blocks are

removed the surfacing material is shaken 50 off and the blocks may be finished in any manner desired or used as they come from the mold.

I of course do not wish to limit myself to the shape, proportions or precise arrangement of parts but desire to cover my invention broadly as set forth in the appended claims.

I claim:

1. A molding apparatus, including a box, 60 tapering hollow core members secured to one member of the box and adapted to receive sand therein, removable open-ended mold members enclosing the core members and spaced therefrom and adapted to receive 65 cementitious material therein, spacers adapted to hold the mold members in spaced relationship, and a frame adapted to cover the spaces between the mold members and provide openings into the mold members for the 70 pouring of cementitious material into the mold members.

2. A molding apparatus, including a box, a plurality of open-ended mold members located in the box, spacing devices between the 75 mold members and the mold members and the box holding said mold members uniformly arranged in the box, and a frame adapted to cover the spaces between the mold members and having openings therein registering with the open ends of the mold members 80 for the pouring of material into the mold members.

3. A molding apparatus, including a box, a plurality of open-ended mold members located in the box, spacing devices between the 85 mold members and the mold members and the box holding said mold members uniformly arranged in the box, a frame adapted to cover the spaces between the mold members and having openings therein registering with the open ends of the mold members for the pouring of material into the mold members, open-ended hollow core members positioned within the mold members, and a box 90 member to which all of said core members are secured.

ALEXANDER MASZTICS.
